UNITED STATES PATENT OFFICE.

FREDERICK R. CORNWALL, OF ST. LOUIS, MISSOURI, ASSIGNEE TO WILLIAMS PATENT CRUSHER AND PULVERIZER COMPANY, OF ST. LOUIS, MISSOURI, A CORPORATION OF MISSOURI.

SIDE-CLOSING PLATE FOR GRINDING-MILLS.

1,377,615.

Specification of Letters Patent. Patented May 10, 1921.

Application filed January 12, 1920. Serial No. 350,908.

To all whom it may concern:

Be it known that I, FREDERICK R. CORNWALL, a citizen of the United States, residing at St. Louis, Missouri, have invented a certain new and useful Improvement in Side-Closing Plates for Grinding-Mills, of which the following is a full, clear, and exact description, such as will enable others skilled in the art to which it appertains to make and use the same, reference being had to the accompanying drawings, forming part of this specification.

My invention has relation to improvements in side closing plates for grinders, pulverizers and like machines and consists in the novel details of construction more fully set forth in the specification and pointed out in the claims.

The object of my invention is to provide a side closing plate for mills that may be secured into position without the use of bolts or similar securing devices. A further object is to provide a closing plate which may be readily attached and detached and at the same time will be positively fixed in position. Further objects are to provide a side closing plate that is simple, durable, and one that may be cheaply manufactured.

Further objects will be better apparent from a detailed description of the invention in connection with the accompanying drawings, in which—

Figure 1 is a side elevation of the mill with part, however, in section on the line 1—1 of Fig. 2, showing my invention applied to the opening in the side of the mill.

Fig. 2 is an end elevation of the mill with part broken away.

Fig. 3 is a view similar to Fig. 1 showing a modified form of closing plate.

Fig. 4 is a view similar to Fig. 2 only a fragment of the mill being shown, however.

Fig. 5 is a further modified form of the invention.

Fig. 6 is a horizontal section on the line 6—6 of Fig. 5.

Referring to the drawings, M represents a mill, grinder or like machine provided with a shaft S, the shaft being supported in suitable bearings (not shown) which are mounted in the bearing housing H. The housing H is connected to the mill M by means of a web W substantially semicircular in shape. In the sides of the mill are openings O to permit the shaft and rotor to be inserted into

the mill. The closing of this opening O is the subject of my invention, and I have provided means of closing the same whereby I take advantage of the proximity of the web to the opening O in securing my improved closing plate. The web W is provided with a groove 1, and in this groove, is seated my improved cover plate consisting of complementary members, 2, 2'. It will be observed that to seat these plates in the groove 1 it is necessary that they be inserted from above the web, thus requiring slots 3, 3' whereby they may be passed over the shaft S. In positioning the plates 2, 2' over the opening, I first drop the plate 2 over the shaft which passes through the slot 3, seating the said plate in the groove 1. Now when the second plate is placed over the opening, it is necessary that the slot 3 of the plate 2 be rotated a sufficient distance in order that the slot 3' of the plate 2' will not be in alinement therewith. In Fig. 1, I have shown the slot 3 rotated to a position diametrically opposite to that of the slot 3', but any amount of rotation is sufficient provided the two slots 3, 3' are not in alinement. After the plates have been rotated to their proper positions, the slots 3, 3' being opposite the body of the plates 2', 2, it will be seen that the opening O in the mill is effectively closed.

It will be understood that in grinding mills, it is desirable to close up the mill as effectively as possible in order that no dust or other substance will escape from the mill into the room where it is located.

Referring now to Figs. 3 and 4, I have provided a modified form of cover plate comprising a principal plate 4, which has a slot 5 to permit its being passed over the shaft S, but in lieu of a second cover plate, I merely use a complementary plate 6 adapted to fit in the slot, thus closing it. In this form, the shaft S has an annular groove 7 in alinement with the groove 1, and in positioning the closing plate, it is passed over the shaft and the base of the slot is seated in the groove of the shaft, the periphery of the plate being seated as before in the groove 1. The complementary plate 6 is likewise seated in both grooves 7 and 1.

In assembling the plate 4, it is necessary, after it has been positioned in the groove 7, to rotate the plate clear of the web W, when the plate 6 can be inserted (see dotted po-

110

sition, Fig. 3), after which the assembled plates are positioned, as shown in Fig. 3. It will be seen that when the plates 4 and 6 are assembled, the slot 5 is tightly closed, 5 and we have the equivalent of a solid plate.

In Figs. 5 and 6, I have shown an additional modification consisting of a principal plate 8 provided with a slot 9 and a complementary plate 10 adapted to close said slot, 10 said plate 10 being held in position by the sides of the slot and confining fingers 11, as shown more clearly in Fig. 6.

From the foregoing description, it will be seen that I have provided a side closing 15 plate whereby the opening in the mill is effectively closed without the use of bolts, rivets, or the like, the plates being readily placed in position and removed.

It is obvious that the invention is susceptible of modifications without departing 20 from the spirit thereof, and of all of these I wish to avail myself.

I claim:

1. In combination with a mill provided 25 with a side opening, a shaft, a rotatable circular closing plate for said opening comprising a member provided with a slot, and means for closing said slot.

2. In combination with a mill, provided 30 with a side opening and a shaft, a rotatable circular closing plate or cover comprising complementary members for closing said opening.

3. In combination with a mill provided 35 with a side opening and a shaft, means for closing said opening and comprising a rotatable circular plate with a radial slot, and means for closing the slot.

4. In combination with a mill provided 40 with a side opening and a shaft, means for closing the opening comprising a rotatable circular plate with a radial slot and a complementary plate adapted to close said slot.

5. In combination with a mill provided 45 with a side opening and a shaft, means for closing said opening, said means comprising superposed rotatable circular plates.

6. In combination with a mill provided 50 with a side opening and a shaft, means for closing said opening, said means comprising

superposed rotatable circular plates provided with slots, said slots being angularly arranged with relation to each other when the plates are rotated in position to cover the opening. 55

7. In combination with a mill provided with an opening, a laterally extending web provided with a semi-circular groove adjacent the opening and concentric to the shaft, a rotatable circular closing plate for said opening, said plate being provided with a slot adapted to receive the shaft when the plate is seated in said groove, and means for closing said slot. 60

8. In combination with a mill provided 65 with an opening, a shaft extending therethrough and a laterally projecting web provided with a groove adjacent part of the periphery of said opening, rotatable complementary plates for closing the opening, 70 the plates being provided with slots for receiving the shaft and being adapted to seat in said groove, the slots being angularly disposed when the plates are seated and rotated relative to each other. 75

9. In combination with a mill provided with an opening, a shaft extending therethrough, and a laterally projecting web provided with a groove adjacent part of the periphery of said opening, a slotted plate 80 for closing said opening and rotatably positioned in said groove, and a second plate positioned in the groove and over the first plate, said plates being capable of relative rotation in the groove to close the opening 85 in the first plate.

10. In combination with a mill provided with a side opening, a shaft extending therethrough, and a laterally projecting web provided with a groove adjacent part of the 90 periphery of said opening, an annular groove in said shaft in alignment with the groove in the web, and a slotted plate for closing the opening, said plate being seated in the groove of the shaft and the groove in 95 the web, and being capable of rotation in the groove, and means for closing said slot.

In testimony whereof I hereunto affix my signature this 7th day of January, 1920.

FREDERICK R. CORNWALL.
